PANEL STRIP FOR GATES

Jene F. Ford, Goshen, Ind., assignor to Star Tank and Boat Company, Goshen, Ind., a corporation of Indiana

Filed May 12, 1965, Ser. No. 85,239

Term of patent 14 years

(Cl. D54—2)

FIG. 1

The characteristic feature of my design resides in the longitudinal intermediate bead portions in combination with the curved central portion.

I claim:

The ornamental design for a panel strip for gates, as shown and described.
